SASH ASSEMBLY

Richard D. Hughes, Clayton, and Joseph M. Kountzman, Senior, Kimmiswick, Mo., assignors to Cupples Company, St. Louis, Mo., a corporation of Missouri

Application December 3, 1951, Serial No. 259,566

4 Claims. (Cl. 160—101)

1

This invention relates to improvements in window assemblies generally, but more particularly to double hung window assemblies of both the vertical and side sliding types.

A principal object of this invention is to provide a window assembly with frame means to accommodate interchangeable storm sash and screen panels which are easily applied and removed from within the building.

An object of this invention is to provide an improved window construction for all-metal windows or for metal sash windows having insulation or thermally inert means for retarding the heat transmission through the sash, thus insulating the sash and overcoming objectionable moisture condensation and formation of ice on the sash.

It is also an object hereof to provide a double hung window assembly of both vertical and side sliding types having means between the sliding sash for receiving the interchangeable storm sash and screen panels, such means being an insulator to retard heat transmission through the storm sash and to reduce the likelihood of condensation or ice formation.

The invention consists in a window assembly including a frame with sash sideways separated by jamb parting strips and head and sill rails made of insulating material, and further including a cross rail located between the meeting rails of the sliding sash when in normal closed position. The invention also consists in the provision of sash parting strips and rails adapted to receive interchangeable storm sash and screen panels in the space between the sliding sash. Moreover, this invention consists in the parts of the window assembly and in the combination of parts thereof, as may be described and claimed hereinafter.

It has been a problem in connection with the use of all-metal or wood window frames and metal sash to avoid the objectionable formation of condensation or ice in and around the margins of the window assembly. At the present time, nothing has been made available which will eliminate or reduce this objectionable feature. The present invention is addressed to the problem of reducing, if not eliminating, the objectionable feature of condensation or ice formation on or around the sliding metal sash. This object of the invention is attained by insulating the metal sash through the application of parting strips and rails formed of insulating material. Any suitable insulating material may be employed for these parts of the window structure,

2

such as wood, plastic or similar thermally inert materials.

The invention is exemplified by a presently preferred window assembly and by certain modifications adapted to the use of various materials shown in the accompanying drawings, wherein:

Fig. 1 is an elevational view of a window assembly seen from the interior side thereof;

Fig. 2 is an enlarged sectional elevation with portions broken out, the view being taken at line 2—2 in Fig. 1;

Fig. 3 is an enlarged, fragmentary transverse section taken at line 3—3 in Fig. 2;

Fig. 4 is an enlarged fragmentary detail showing a typical locking provision for the removable storm sash and screen panels;

Fig. 5 is a view similar to that of Fig. 2, but illustrating a modification which is an all metal window assembly; and,

Fig. 6 is a further modification of the present invention showing an all wood window assembly in fragmentary detail only.

Referring in particular to Figs. 1, 2 and 3, a preferred construction is shown in connection with a window frame utilizing wood parts and having metal sash therefor. The window frame 10 includes the sill 11, the lintel or head 12 and the jambs 13, all of which are arranged in a known manner to receive in sliding relation metal sash consisting of the upper or outer sash 14 and the lower or inner sash 15. Each metal sash is provided with the usual glass pane 16.

In Fig. 2, the lintel or head 12 includes a head member 20 provided with an outer stop rail 21 and an inner bead 22. The head 20 also carries an intermediate rail 23 which cooperates with the stop 21 to form an outer slideway 24 for the outer sliding sash 14. In like manner, rail 23 cooperates with the bead 22 to form an inner slideway 25 for the inner sash 15. Each of the jambs 13 includes a jamb member 17 (Fig. 3) provided with an outer stop member 26 (which cooperates with the head stop member 21) and an inner bead 27 (which cooperates with the bead 22 carried by the head 20). In addition, each jamb member 17 carries a parting strip 28 which is adapted to cooperate with the parting rail 23 of the head 20 to separate the outer slideway 24 for the sash 14 from the inner slideway 25 for the sash 15. The jamb member 17 of Fig. 3 is duplicated by one opposed thereto in the frame assembly. The sill 11 includes a sill member 18 which carries a rail 30 adapted to cooperate with the parting strips 28 carried by the respective jamb members 17 so that the sliding sash 14 and

15 having slideway throughout the vertical extent of the frame assembly. The sill member 18 carries at its inner margin a moulding strip 31, as is understood.

The head rail 23, Fig. 2, is provided with an outer stop 33 formed by the rabbet 34. In like manner, the sill rail 30 is provided with stop 35 formed by the rabbet 36 and each of the jamb parting strips 28 (Fig. 3) is provided with the stop 37 formed by a rabbet 38. The cross rail of this assembly is shown at 40, and this rail is located between the meeting rails 15A and 14A of the sliding sash 15 and 14, respectively, when in their closed position. Cross rail 40 is provided with outer stops 41 and 42 and is provided inwardly thereof with locating means 43 and 44 at the upper and lower sides thereof. The cross rail may also be provided with suitable weather stripping elements, such as that shown at 45 and 46, adapted to be engaged by the respective meeting rails 14A and 15A when the sliding sash is disposed in closed position.

The respective rails 23, 30 and 40, together with the parting strips 28 carried by the opposite jamb members 17, form intermediate frame elements of the window assembly. These frame elements are formed from insulating materials and act to separate and insulate the outer and inner sliding sash members 14 and 15, so that there is no direct contact therebetween. In addition to this feature, these rails and strips constitute a frame assembly in which removable and interchangeable storm sash and screen panels may be placed without necessitating the usual hazard of mounting the storm sash or screen panels from the outside of the building. The typical storm sash 50 in Fig. 2 is provided with a channel frame so that one side of the frame may be mounted over the locating means 43 on the cross rail 40. The remainder of the frame will then be located against the stop means 33 and 37 heretofore described. In a like manner, the lower storm sash 51 has its upper channel frame member located over the locating means 44 on cross rail 40. The remainder of its frame will then be seated against the stop means 37 and 35.

In Figs. 1, 3 and 4, suitable locking means has been shown for the purpose of retaining the storm sash 50 and 51 in position. This locking means comprises a plurality of detents 52, a typical one being shown in Figs. 3 and 4 pivoted in the parting strips 28 at 53. Each detent 52 can be moved to a position projecting from a suitable recess 54, as shown in connection with Figs. 3 and 4. When so projected, each detent 52 lies against the inner face of the storm sash frame, but when pivoted into the recess 54 is entirely removed from any obstructing relation with the storm sash frame. As shown in Fig. 1, a pair of locking detents 52 have been shown for the upper storm sash 50 and a similar pair 52 have been shown in dotted outline for the lower storm sash 51. Screen panels are mounted in like manner, as shown in fragmentary part only in Fig. 6. In the construction of the screen panels such as that shown at 55 in Fig. 6 a frame substantially similar to and interchangeable with the storm sash 50 and 51 is employed and a suitable screen material 56 is mounted in the frame.

What has been described in connection with Figs. 1, 2 and 3 with respect to the vertical sliding sash type window assemblies shown, applies equally as well to the window assembly having side sliding sash. In a similar way, the provision for mounting removable storm sash 50 and 51

for interchangeable screen panels 55 is readily cared for by utilizing the cross rail and parting strip provisions herein described.

Fig. 5 illustrates a modification which includes 5 an all-metal window frame and sash assembly. In general, the all-metal frame includes the sill 69, the head 61 and the jamb members 62 for each side extending between the sill and head. Only one jamb member 62 is shown however. This frame provides an inner slideway 63 for the inner metal sash 64 and an outer slideway 65 for the outer metal sash 66. The slideways 63 and 65 are separated by means of a head rail 67, a sill rail 68, a jamb rail 69 (one being carried by the opposite jamb member 62 not shown) and the cross rail 70 which is disposed to lie between the meeting rails 64A and 66A of the inner and outer sliding sash, 64 and 66 respectively. These frame elements 67, 68, 69 and 70 are formed of an insulation material such as wood or plastic, for example, and are suitably recessed or rabbeted to receive the interchangeable storm sash 50 and 51 and screen panels 55 heretofore described in connection with Fig. 2 and Fig. 6. Here again, the cross rail 70 is provided with an upper locating means 71 for the storm sash 50 and a lower locating means 72 for the storm sash 51. While not shown in Fig. 5, it is understood that the locking detent 52 of Fig. 4 may be utilized for securing each of the storm sash units in place in this modified window. It is pointed out, in connection with the all-metal window frame and sliding sash, that the insulation material of the head, sill and cross rails and parting strips prevents any metal-to-metal contact of the sliding sash 64 and 66 with each other or with the metal storm sash 50 and 51. The interruption of metal-to-metal paths of heat transfer materially contributes to the reduction in formation of condensation or ice in or on a window assembly of this type.

In Fig. 6 there is illustrated a further modified window assembly showing the all wood construction thereof. This view is similar to that of Fig. 3 and similar parts in Fig. 6 have been indicated by similar numerals of reference increased by one hundred. Accordingly, this modified construction includes a cross rail 140 of the type shown at 40 in Fig. 2, a parting strip 128 for each 45 jamb member 117 and slide ways 124 and 125 for wood sash. A fragmentary portion of a typical wood sash is shown at 75 in the outer slideway 124. Where the frame is made of wood, it is preferred to form the frame elements, such as the head, sill and cross rails and jamb parting strips, of wood also.

What is claimed is:

1. A window construction comprising a frame structure having slideways in spaced planes, an upper sash slidably carried in one of said slideways and a lower sash slidably carried in another of said slideways, a lower rail on said upper sash and an upper rail on said lower sash, said rails having a spaced relation with said upper sash raised and said lower sash lowered, respectively, opposed parting strips and interconnecting head and sill rails carried by said frame structure between said spaced slideways for separating the latter, a cross rail spanning said frame and located in a position to lie between said spaced lower and upper sash rails and be engaged thereby with said upper sash raised and said lower sash lowered, said parting strips and head and sill rails having stop means thereon and said cross rail having locating means at opposite sides, sash

frames located by and cooperating with said parting strips, head and sill rails and said cross rail between said window sash, said sash frames engaging said cross rail locating means and being located thereby in position to engage said stop means, and means releasably retaining said sash frames engaged with said locating means and stops means.

2. The window set forth in claim 1 wherein said window sash are metallic, and said parting strips, head and sill rails, and cross rail are formed of thermal insulating material to separate said metallic window sash and retard heat transmission therebetween.

3. The window set forth in claim 1 wherein said frame structure is metallic, said window sash are metallic, said sash frames are metallic, and said parting strips, head and sill rails, and cross rail are formed of insulating material to separate said metallic parts of the window and retard heat transmission therebetween.

4. In a window construction, a frame structure, opposed parting strips fixed in said frame, spaced head and sill rails carried in said frame in alignment with said parting strips, a cross rail fixed 25 between said parting strips intermediate the spacing of said head and sill rails, stop members on said frame at one side of said parting strips and

5 head and sill rails defining therewith a slideway for a sliding sash, a sash mounted in said slideway, bead members on said frame at the opposite side of said parting strips and head and sill rails defining therewith a second slideway for a sliding sash, a second sliding sash mounted in said second slideway, and sash frames removably cooperating with and located between said parting strips, cross rail and head and sill rails, said removable sash frames being separated by said fixed cross rail and lying between said slideways, each of said sliding sash mounted in said slideways having cross rails located in spaced adjacency with one sliding sash raised and the other sliding sash lowered, said sliding sash cross rails engaging said fixed cross rail in the last mentioned position of said sliding sash.
